UNITED STATES PATENT OFFICE

2,069,581

POWER OPERATED TOOTH BRUSH

John C. Hyde, Chicago, Ill.

Application February 14, 1936, Serial No. 63,964

1 Claim. (Cl. 15—23)

This invention pertains to that classification of structures assembled or grouped under the subdivision of dental appliances and machines and has reference in particular to an electric motor-driven toothbrush workable to advantage in the home for individual and daily usage.

That the art to which the invention relates has been well worked and is characterized by similar structures, is a fact which cannot be doubted. Notwithstanding this general state of the prior art to which the invention relates, I have, after due deliberation and consideration, provided an appreciably distinct brush construction which is calculated to obtain the desired end or result through the instrumentality of well chosen structural adaptations mutually coacting to provide requisite features of refinement and improvement.

It goes without saying that my primary objective is to generally improve upon similar marketed and patented dental brushes by providing a proportionately new assemblage, wherein the essential novelty is directed to the mechanism utilized in the construction and perfection of the brush per se with the end in view of utilizing appropriately selected details which, when assembled, insure requisite efficiency, economy and dependability.

Other features, objects and advantages will become more readily apparent from the following description and drawings.

In the accompanying drawings, wherein like numerals are employed to designate like parts throughout the views,

Figure 1 is an elevational view showing the complete assemblage including the motor, the flexible shaft and the improved brush on the operating end of the shaft.

Figure 2 is a view, in section and elevation, illustrating the mechanism selected to construct the improved toothbrush.

Figure 3 is a detail view, primarily in elevation, of the brush accommodation and drive shaft or mandrel.

Figure 4 is a cross section, on an enlarged scale, taken approximately on the plane of the line 4—4 of Figure 3.

Figures 5, 6, and 7 are perspective views of certain of the complementary parts and accessories.

Figures 8 and 9 are elevational views of modified styles or types of toothbrushes usable in the special holder.

Referring now to the drawings by distinguishing reference numerals, it will be observed that

the portable electric motor is indicated by the numeral 10. This is of a type, universal in character, to adapt it for domestic or home use. The flexible drive shaft, which may be of any construction, is indicated by the numeral 11 and is connected to the motor through the instrumentality of proper speed-reducing gearing means 12 (not illustrated in detail). On the free end of the shaft is a suitable coupling type drive fitting which as shown in Figure 5 comprises an appropriate union 13 and a flat-faced mandrel or shaft rotating key 14.

At this point in the description it might be mentioned that the expression "toothbrush" may be used to describe the unitary assemblage shown especially in Figure 2. It is evidence, however, that the toothbrush as an element is denoted by the numeral 15 and is a detachable part and that the essential novelty is in the holder or handle means which serves to accommodate it. Moreover, different types of toothbrushes may be used such as for example those indicated by the numerals 16 and 17 in Figures 8 and 9. In each instance the brush includes a driving stem 18 and an appropriate bristle or otherwise constructed head 19.

Considering the structure so far detailed, it is observed that the novelty in general may reside in the combination of the motor shaft and brush and its holder, though the principal novelty is predicated upon the construction of the holder itself. Referring then to Figure 2, it is to be noted that the tubular casing 20 is utilized as a mechanism housing as well as the operating and controlling handle. This is truly cylindrical and open at its opposite ends. Intermediate its ends it is formed with an internal annulus 21 which defines a bearing for the driven shaft or mandrel 22. At the lower end in Figure 2 the shell is counterbored to form a socket to accommodate the various parts contained therein. One part is the bushing 23 against which the headed end 24 of the shaft bears. Incidentally, this headed end is formed with a socket 25 to accommodate the operating key 14. Correlated with the bushing 23 and head assemblage is a special fitting or adapter 26 which is slipped into the lower end of the tubular shell or casing and held in place by a screw or similar fastening 27. This has a central bore and a double socket. The inner socket 28 serves to accommodate the driving head 13. The outer socket serves to accommodate the flexible shell of the drive shaft 11. Hence, it is evident that the bushing 23 can be slipped into the tube 20 against the retention shoulder. Then the shaft 25

22 can be readily assembled and finally the part 26 and its fittings can be inserted to insure effective operation and to expedite assembling and proper maintenance of parts.

- 5 Referring to the opposite end of the shaft, it will be observed that this is formed with a screw-threaded tapered chuck 29 to accommodate the stem of the brush. Inwardly of the chuck is a passage 30 which serves to accommodate a stay pin 34. This pin is adapted to be inserted through a hole 32 in the casing and then through the passage 30 to temporarily lock the mandrel or shaft against rotation while applying and removing tooth brushes. This is a 10 safety feature which contributes materially to the success of the invention and makes it substantially fool-proof.

The chuck is rendered effective through the instrumentality of a clamping collar 33, which 20 collar is formed with a tapered screw-threaded socket for expansion and contraction of the grips of the chuck. The collar is made to fit completely within the housing or casing 28. It is formed with spanner wrench sockets 34 to accommodate the pins 35 on the simple spanner wrench 36 shown in Figure 6. This comprises a knurled finger-grip 37 having an accommodation notch 38 to accommodate the stem of the brush. This provides a convenient means of adjusting 25 the collar 33 to facilitate application and removal of the toothbrush 15.

It is evident that the mechanism selected to form the holder for the toothbrush is united so that the various features mutually cooperate in 30 providing the desired continuity and safety of operation. This appropriate selection and adaptation provides a sturdy and reliable brush holder. It makes for simplicity, economy, and efficiency. Under the circumstances it is be-

lieved that this form of a holder should constitute a novel contribution to the art and trade whose features of refinement and adaptability may be unqualifiedly endorsed.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

A power-operated toothbrush comprising a holder including an open-ended tubular cylinder forming a combined handle and mechanism casting and provided on its interior intermediate its ends with an annulus constituting a bearing and provided at one end with a counter-bore, a bushing fitted into the counter-bored end of the cylinder and abutting the shoulder formed through the instrumentality of said counter bore, said bushing being of such a cross-sectional diameter that the bore thereof matches the bore in said bearing, a mandrel confined in said cylinder and mounted for rotation in the bushing and bearing, said mandrel being provided with a brush clamping chuck, the driven end of the mandrel extending outwardly beyond the bushing and having an outstanding abutment flange in rotating contact with said bushing, an adapter collar fitted into the counter-bored end of the cylinder and in contact with said flange and constructed to accommodate a flexible driving shaft 35 cooperable with the mandrel.

JOHN C. HYDE.
